UNITED STATES PATENT OFFICE.

HENRY STAFFORD GOLLAND, OF MANCHESTER, ENGLAND.

MEANS FOR CROSS-WINDING YARN IN SPINNING-MULES.

1,144,652.

Specification of Letters Patent. Patented June 29, 1915.

Application filed December 30, 1914. Serial No. 879,652.

To all whom it may concern:

Be it known that I, HENRY STAFFORD GOLLAND, a subject of the King of Great Britain and Ireland, residing at "Dunstan," 5 Eccles, Manchester, in the county of Lancaster, England, merchant, have invented new and useful Improvements in Means for Cross - Winding Yarn in Spinning - Mules, of which the following is a specification.

10 The invention relates to means for cross-winding yarn in spinning mules, and is an improvement upon inventions for which I have obtained United States Patents Nos. 750,026 and 873,422. In these prior patents 15 I described the use of an auxiliary yarn guide wire disposed between the spindle and the winding faller wire and under the yarn, which guide wire was vibrated and during the run in of the mule carriage acted upon 20 the yarn to direct it in widely pitched spirals upon the cop nose to produce what is known as a cross-wound cop.

The object of my present invention is to 25 simplify the means used to vibrate this auxiliary guide wire, the mechanism being also reduced very greatly in weight and bulk to that shown in my latter patent referred to, No. 873,422.

30 The gist and essential novelty of my invention is to vibrate the auxiliary guide wire by mechanism actuated through the winding faller shaft, which shaft I have caused to oscillate or rock upon its center during the winding operation by providing 35 the coppering rail with a wavy or undulating surface so that the winding faller wire is raised and lowered to a slight degree several times during the run in of the mule carriage. Instead of using a wavy coppering rail other 40 means may be adopted to rock the winding faller shaft, such for instance as applying an eccentric bowl to the boot leg slide such bowl running on the coppering rail.

45 Although I will now describe means suitable for the purpose of carrying my invention into effect I wish it to be understood that I do not confine myself to such means as they may be varied in point of mechanical detail.

50 In the accompanying drawings which clearly illustrate the invention, Figure 1 shows a side elevation of my improved mechanism. Fig. 2 is a view at right angles thereto. Figs. 3 to 6 are detail parts. Fig. 55 7 is a side view of the coppering rail with in-

clines applied thereto, and Fig. 8 is a view of the back coppering plate and which is made to the same height and angle as the front plate such front and back coppering plates being used to effect the horizontal 60 lowering of the coppering rail to gradually raise the position of the winding faller wire during the building of the cops.

The auxiliary guide wire referred to is marked *a* and is carried by fingers *b* one at 65 each end of the winding faller shaft *c* at each side of the headstock and loosely mounted on such shaft. In addition any suitable number of sickles *d* are used at intervals to carry the auxiliary guide wire *a*, 70 and these sickles *d* are also mounted loosely upon the winding faller shaft.

The auxiliary guide wire *a* is disposed, as in my former invention, between the winding faller wire *e* and the spindles *f* and 75 beneath the yarn, the winding faller wire *e* being carried by sickles *g* secured to the winding faller shaft *c* in the usual manner.

The mechanism illustrated in the drawings for vibrating the auxiliary guide wire *a* 80 is mounted on the winding faller shaft *c* at each side of the headstock. The drawings show the mechanism at one end of the winding faller shaft *c* only, the shaft *c* carrying duplicate mechanism for each finger *b* and 85 sickle *d* along the entire length of the mule carriage. The fingers *b* are each provided with a stud, bowl or the like *g'* resting upon a cam *g'*, and a similar stud *g''* is also carried by each sickle *d* secured to a tail *d'*. 90

The ordinary movements of the winding faller shaft *c* are imparted thereto by mechanism at present in use for that purpose.

To obtain the additional oscillating movement of the winding faller shaft *c*, which 95 under my invention it is necessary it should have, as well as its usual movements, the coppering rail is provided with a number of double inclines *h* as shown in Fig. 7, so that when the bowl *h'* of the usual rail lever or 100 boot slide runs up and down these inclines, the winding faller shaft *c* will be rocked or oscillated on its center. The mechanism actuated from the oscillating or rocking motion of the winding faller shaft *c* is 105 adapted, during the winding operation, to vibrate the cam *g'* to move the fingers *b* up and down, and at the same time to rock the cam to some extent upon, and rotate it around, a center. The extent of vibration 110

of the cam is constant, but the vibration of the fingers *b*, and with them the auxiliary yarn guide *a* is gradually increased from a minimum to a maximum. The minimum vibration of the fingers *b* and the sickles *d* is effected at the commencement of the formation of the cop bottom when the guide wire *a* is to raise and lower the yarn to a minimum degree, and as the cop bottom is being formed the vibration of the guide wire *a* is gradually increased by rotating the cam to bring an increasing diameter of the surface of the cam into action to give a gradually increased lift to the sickles until the cop bottom is formed and the full length of chase of the cop nose is obtained. This maximum lift of the guide wire *a* is then maintained throughout the building of the cops. This building of the cops is effected by the action of the usual copping motion upon the winding faller shaft, which, besides being rocked, is slowly rotated to very gradually lift the winding faller wire as is well understood. When spinning is taking place and the winding faller wire is lifted as usual above the tips of the spindles, I arrange also that the auxiliary guide wire *a* shall be similarly lifted but to a point below the tops of the spindles, so as not to come into contact with the threads during the spinning operation.

The vibrating of the cam *g'* about the center of the winding faller shaft *c* and the rocking and rotating movement of the same are effected as follows. The cam *g'* is shown separately in face view in Fig. 5 and it is loose on a stud *g²* which stud is carried loosely in a bracket or part *i* which is also mounted loosely on the winding faller shaft *c* and on the same stud *g²* is secured a spur wheel *g³* meshing with the teeth of a quadrant *g⁴* formed on a bracket *g⁵* mounted loosely on the winding faller shaft *c* and clamped or held to a part *g⁶* of the fixed frame or otherwise secured to prevent it oscillating with the shaft *c*. A toothed quadrant *j* fast on the winding faller shaft *c* and oscillating therewith gears with a toothed quadrant *j'* loosely mounted on a stud *j²* secured to the bracket *g⁵* and a stud or projection *j³* on the quadrant *j'* carries a bowl *j⁴* disposed in a slot *k* in the bracket *i* carrying the cam *g'*. A separate view of the bracket *g⁵* and the parts carried by the same is shown in Fig. 3. The toothed quadrant *j* is also shown separately in Fig. 6.

When the winding faller shaft *c* oscillates or rocks on its center as described during the run in of the mule carriage the quadrant *j* thereon actuates the quadrant *j'* in gear with it and by means of the bowl *j⁴* engaging in the slot *k* in the cam bracket *i* vibrates the cam bracket about the axis of the winding faller shaft *c*, the cam *g'* carried on this bracket causing the finger *b* of the auxiliary

guide wire *a* to be lifted and lowered by reason of such cam acting against the stud *g²* fixed on the finger *b*, the cam being at the same time rocked on its center. At the commencement of the winding of the cops the stud *g²* rests on the smallest diameter of the cam *g'* as shown in Fig. 1. This provides for the minimum lift of the auxiliary guide wire *a* at the commencement of the build of the cop bottom. The lift of the guide wire *a* must be gradually increased as the cop bottom is being formed until the proper length of chase is reached when the extent of lift or vibration of the guide wire *a* remains constant or practically so throughout the rest of the formation of the cops. This gradually increasing lift or vibration of the guide wire *a* is effected by a gradual rotation of the cam *g'* around its axis so as to bring the increasing diameter or incline of the cam to act upon the stud *g²* of the guide wire finger *b*, this rotative movement being effected simultaneously with the rocking of the cam upon its own center and its oscillation about the center of the winding faller shaft *c*.

The rocking and rotating actions of the cam *g'* are effected by a ratchet and pawl motion which is arranged, through the medium of the spur wheel *g³*, to rock or oscillate the cam on its center and at the same time feed it around on its axis. The motion consists of two ratchet wheels *m* *n* secured upon the stud *g²*, on which the cam *g'* is loosely mounted, the teeth of one ratchet wheel being arranged at an angle opposite to the teeth of the other. The cam *g'* carries two spring pawls *m'* *n'* the pawl *m'* being adapted to engage with the ratchet *m* and the pawl *n'* with the ratchet *n*.

In Fig. 1 a part of the ratchet wheel *n* is broken away to show the opposite angle of the teeth of the ratchet wheel *m*. When the cam bracket *i* is oscillated about the axis of the winding faller shaft *c* the stud *g²* is rotated in its bearing in the bracket *i* by means of the spur wheel *g³* which is fixed upon it and meshing with the fixed quadrant *g⁴*. The ratchet wheels *m* *n* being secured upon the stud *g²* oscillate with it. The spring pawl *m'* being adapted to engage with the ratchet wheel *m* is pulled in one direction and being fastened to one side of the cam *g'* pulls the cam *g'* which is loose on the stud *g²*, around its center to the extent of the movement of the ratchet wheel in that direction. When the motion of the ratchet wheel is reversed the stud *n³* which is fixed on the ratchet wheel *n* pushes the cam *g'* in the opposite direction to the extent of its motion in that direction. This oscillation of the ratchet wheel *m* takes place during the inward run of the mule carriage and the winding of the yarn on the spindle, and when this is finished the movement of the faller shaft *c*

c during the delivery or upward movement of the winding faller wire *e* to its position above the spindle point, carries the bracket *i* and with it the cam *g'* to its highest position lifting the wire *a* to a position below the spindle point. The degree of oscillation of the bracket *i* during this movement carries the ratchet wheels around in one direction to a considerable degree but means are provided to limit the rotation of the cam *g'* any farther than will bring its larger diameter beneath the stud *g**. At the point when the cam has been revolved around its center so that its largest diameter is brought beneath the stud *g**, the end *m*² of the spring pawl *m'* comes in contact with the concentric ledge *o'* and is disengaged from the ratchet wheel *m* and ceases to pull the cam *g'* any farther around in that direction. When the backing off takes place and the winding wires are lowered to their initial points the movement of the ratchet wheel *m* is reversed and the stud *n*³ pushes the cam back to its initial position the pawl *m'* again engaging with the ratchet wheel *m*.

As the winding proceeds the initial position of the winding wires is gradually raised by the decreasing of the extent of the movement of the winding faller shaft *c* in the reverse direction, this also decreasing the reverse movement of the bracket *i* and the ratchet wheel *m*. The stud *n*³ likewise being reduced in its reverse movement pushes back the cam *g'* a shorter distance each time and the cam is thus gradually fed around its center and the larger diameter of the cam *g'* comes into operation and increases the length of movement of the wire *a*. When the cop has been built some distance up the spindle the reverse motion for backing off has become gradually shorter until the reverse motion of the stud *n*³ is not sufficient to effect the backward oscillation of the cam *g'* and is inoperative. By this time the end *n*² of the pawl *n'* will be drawn out of contact with the concentric ledge *o* and the pawl *n'* will engage with the ratchet wheel *n*. As soon as the motion is reversed the pawl *n'* being engaged with the ratchet wheel *n* will pull the cam in that direction until the pawl at *n*² again comes in contact with the concentric ledge *o* when the pawl *n'* will be disengaged from the ratchet wheel *n* and cease to effect the movement of the cam *g'* in that direction. The degree of oscillation of the cam *g'* is now controlled in each direction by the spring pawls *m'*, *n'*, the extent of their pull being determined by the point at which *m*² and *n*² meet the concentric ledges *o'*, *o* and disengage the pawls *m'*, *n'* from the ratchet wheels *m*, *n* respectively and alternately. The slot *k* in the cam bracket with which the bowl *j*⁴ of the toothed quadrant *j'* engages is shaped so that the bowl *j*⁴ will not affect the position of the cam bracket after the auxiliary guide wire has been raised to its maximum height below the spindle point preparatory to the spinning operation.

It will be understood that any desired number of sickles for the guide wire *a* and actuating mechanism for such sickles, may be used and a suitable casing for such mechanism may be provided.

I declare that what I claim is.

1. In a spinning mule, means to vibrate an auxiliary yarn guide wire disposed between the spindles and the winding faller wire and beneath the yarn to cause the guide wire to act upon the yarn and direct it upon the cop nose in widely pitched spirals to produce cross wound cops, by mechanism actuated from the winding faller shaft and means to oscillate or rock the winding faller shaft on its center during the winding operation substantially as described.

2. In a spinning mule the combination with the winding faller wire and an auxiliary guide wire, of means to vibrate the winding faller and the auxiliary guide wire during the run in of the carriage substantially as described.

3. In a spinning mule the means for vibrating the winding faller wire during the run in of the mule carriage, an auxiliary yarn guide wire, cams to vibrate such wire, and mechanism for oscillating the cams about the axis of the winding faller shaft and for rocking the cams on their axes and gradually rotating the same to increase the lift of the auxiliary guide wire from a minimum to a maximum as required to form the cop bottom and to continue the building of the cops substantially as described.

4. In a spinning mule the auxiliary guide wire *a*, cams to vibrate such guide wire and means to vibrate the cams to lift and lower the auxiliary guide wire, to rock the cams upon their centers, and to slightly rotate the cams to gradually bring the increasing diameter of such cams in action to vibrate the guide wire from a minimum to a maximum in the manner and substantially as described.

In testimony whereof I have signed my name to this specification in the presence of two subscribing witnesses.

HENRY STAFFORD GOLLAND.
